CLOTHES HOOK

Alwyn R. Bunting, Portsmouth, Va.

Application July 12, 1937, Serial No. 153,286

3 Claims. (Cl. 248—218)

The invention relates to clothes hooks and more especially to self-latching and unlatching clothes hooks.

The primary object of the invention is the provision of a hook of this character, wherein the construction thereof enables the holding of both articles of wearing apparel and head gear and either or both can be removed and on removal of either the remaining article will not be disturbed, the hook in its entirety being of novel construction and will be latched and unlatched in both opened and closed positions and articles when held by the hook when in a closed position will be clamped so that the same can not become accidentally detached therefrom, the latching and unlatching of the hook being automatically effected.

Another object of the invention is the provision of a hook of this character, wherein the articles when hung thereby will be protected from damage and can be readily and easily removed, there being independent holding mediums for body and head gear.

A further object of the invention is the provision of a hook of this character, which is simple in its construction, thoroughly reliable and efficient in operation, neat in appearance, compact, readily and easily handled, strong, durable, and inexpensive to manufacture.

With these and other objects in view, the invention consists in the features of construction, combination and arrangement of parts as will be hereinafter more fully described, illustrated in the accompanying drawing, which discloses the preferred and modified forms of embodiment of the invention and pointed out in the claims hereunto appended.

In the accompanying drawing:

Figure 1 is a side elevation partly in section of a hook constructed in accordance with the invention.

Figure 2 is a front view thereof partly in section.

Figure 3 is a view similar to Figure 1 showing the hook in an adjusted open position.

Figure 4 is a fragmentary elevation of modified adjuncts of the hook illustrated in Figures 1, 2 and 3.

Figure 5 is a front elevation of the modification shown in Figure 4.

Figure 6 is a fragmentary side elevation partly in section showing the jaws of the hook illustrated in Figures 1 to 3 slightly modified.

Similar reference characters indicate corre-

sponding parts throughout the several views in the drawing.

Referring to the drawing in detail, particularly Figures 1 to 3 inclusive, there is shown a hook, wherein the keeper crown 40 formed with the jaw constituted by an arm or tine 41 has pivoted at 42 therein an auxiliary or supplemental jaw in the form of an arm or tine 43 for coaction with and between the arm or tine 41 and the hook body 44. These jaws 41 and 43 in their coaction with each other are for the clamping of a head piece thereby while the arm or tine 43 coacts with the hook body 44. Thus the head piece can be removed from the hook without the removal of the body garment or the latter may be removed from the hook body 44 without removing the head piece from engagement by the tines or arms 41 and 43. The outer end of the auxiliary or supplemental arm or tine 43 has laterally projecting therefrom rubber knobs 45, 20 being in the form of rollers and journaled on an axle 46 fitted with the said end and functioning to avoid damage to garments suspended from or carried by the hook. The arm or tine 41 at its outer end is formed with a rounded relatively 25 wide terminal 47 which avoids damage to an article in the use of the hook.

In Figures 4 and 5 there is shown a further modification, wherein the jaw constituted by an arm or tine 48 at its outer end has fitted 30 therewith the rubber knobs in the form of laterally extended rollers 49, these functioning similarly to the rollers 45.

In Figure 6 of the drawing there is shown a still further modification, wherein a jaw formed 35 by the arm or tine 50 is of a shorter length than the arm or tine 41 and in this manner affording a greater opening capacity with respect to the auxiliary or supplemental jaw constituted by the arm or tine 43 or 48 in association therewith. 40

In Figures 1 to 3 of the drawing the hook-like body 44 has formed thereon a finger hold 51 which projects therefrom and enables the convenient manipulation of the hook for the opening of the same by hand. 45

What is claimed is:

1. A hook of the character described comprising relatively movable members, both movable on a common axis for opening and closing movements relative to each other, a keeper crown on 50 one of the members and disposed over the other member at one end thereof, a latching means coacting with the crown for latching the members in opened or closed relation to each other, a hanger bracket swingingly supporting the said 55

members, and an auxiliary member coactive with the members.

2. A hook of the character described comprising relatively movable members, both movable on a common axis for opening and closing movements relative to each other, a keeper crown on one of the members and disposed over the other member at one end thereof, a latching means coacting with the crown for latching the members in opened or closed relation to each other, a hanger bracket swingingly supporting the said members, an auxiliary member coactive with the members, and stops associated with the bracket and said crown for coaction with one of the members for limiting the swinging action of both members having the common axis.
- 5 10 15

3. A hook of the character described comprising relatively movable members, both movable on a common axis for opening and closing movements relative to each other, a keeper crown on one of the members and disposed over the other member at one end thereof, a latching means coacting with the crown for latching the members in opened or closed relation to each other, a hanger bracket swingingly supporting the said members, an auxiliary member coactive with the members, stops associated with the bracket and said crown for coaction with one of the members for limiting the swinging action of both members having the common axis, and resilient terminal means associated with one of the members. 10 15
